UNITED STATES PATENT OFFICE

SAMUEL RICHMOND, OF BATAVIA, OHIO, ASSIGNOR TO THE EDWARDS MANUFACTURING COMPANY, OF CINCINNATI, OHIO, A CORPORATION OF OHIO

SHOE-SHANK SUPPORT

Application filed March 24, 1928. Serial No. 264,393.

This invention relates to shoe shank supports and particularly to shoe shank supports for the so-called arch supporting type of women's shoes.

5 An object of this invention is to provide a simple, inexpensive metal member for the purpose set forth and one which permits of the proper disposition of the insole relative to the outer sole in shoes of the class referred 10 to.

Another object is to provide an integral sheet metal support member for this purpose.

Another object is to provide a device of 15 this kind which may be adapted to various shapes of shoe shanks.

These and other objects are attained by the means described herein and disclosed in the accompanying drawings, in which:

20 Fig. 1 is a perspective view of a metal shank support of the invention.

Fig. 2 is a perspective view of a modified device of the invention.

Fig. 3 is a perspective view of still another modification of the device of the invention.

The device of the invention comprises a sheet metal body having its rear end 6 suitably formed for attachment to the heel of a 30 shoe and having an angularly disposed opposite end 7. The metal shank support is adapted for insertion between the inner and outer soles of a shoe. The outer sole conforms to the shape of the metal support member while the insole does not have the relatively abrupt curve therein as in the metal shank support and outer sole. The space between the shank support and inner sole at the angular portion of the shank support is in the device of the present invention bridged by integral means supported in spaced relation to the angular portion 7 of the metal shank support comprising integral arched strips 8 which are struck from the body of the portion 7 and 40 which have imparted thereto a relatively opposite curvature to that of the body portion 7. As shown in Figs. 1 and 2 the arched strips 8 may extend in substantial parallelism with the longitudinal axis of the shank support, while as shown in Fig. 2 the integral arched

strips 8 may extend transversely of the longitudinal axis of the shank support. The strips 8 as will be readily appreciated may be cut free from the body 5 and 7 and formed to the desired shape in one operation. The 55 fabrication of the metal shank supports is therefore principally a punch press operation. These strips may be one or more in number and may be brought to support an insole at one place in a given plane and with 60 a certain desirable degree of resiliency. It will be understood that it is not essential to the invention that these strips 8 form a resiliency support, since the primary object of the device is to provide a shoe shank support 65 which may receive on opposite sides thereof an inner sole and outer sole and retain them in a desired relation, spaced at one place to permit the manufacture of shoes according to certain styles and design and at the same 70 time provide strength and comfort. It will be appreciated however that a desirable resiliency may be imparted to that portion of the shoe which lies just at the front or forward portion of the arch by employing shank 75 supports of the kind herein illustrated.

What is claimed is:

1. In a metal shank support for shoes the combination of a metal body, an angularly disposed end on said body and integral strips 80 struck from the angularly turned portion of the body, said strips being disposed in spaced relation to said turned portion to provide a slotted supporting surface in a plane spaced thereto.

2. In a shank support the combination of an elongated metal body having strips cut therefrom at its anterior end and formed away from the body to increase the operative thickness of the metal body at one point for 90 spacing superposed members at different distances from one another at different places along the metal body.

3. A metal shank support having its forward end slotted to provide strips, said strips 95 being alternately bent in opposite directions.

4. A sheet metal shank support having an angularly disposed end portion and integral strips struck therefrom and raised out of the plane of the angularly disposed portion to 100

provide a supporting means spaced from the angularly disposed portion.

5. A metal shank support for shoes comprising a formed strip of sheet metal having its forward end enlarged and slotted to provide strips, adjacent strips being bent in opposite directions and providing spaced supporting means for superposed shoe sole members between which the shank support may be mounted.

10. In testimony whereof, I have hereunto subscribed my name this 9th day of March, 1928.

SAMUEL RICHMOND.
